UNITED STATES PATENT OFFICE.

JAMES E. PHINNEY, OF CHICAGO, ILLINOIS.

DESIGN FOR A LAMP.

43,203.

Specification for Design.

Patented Oct. 29, 1912.

Application filed September 4, 1912. Serial No. 718,581. Term of patent 3½ years.

To all whom it may concern:

Be it known that I, JAMES E. PHINNEY, a citizen of the United States, residing at Chicago, in the county of Cook and State of Illinois, have invented a new, original, and ornamental Design for Lamps, of which the following is a specification, reference being had to the accompanying drawing, in which a perspective view of the design is shown.

I claim:

The ornamental design for a lamp, as shown.

In testimony whereof I affix my signature in the presence of two witnesses.

JAMES E. PHINNEY.

Witnesses:

S. J. LEHRER,
H. G. BATCHELOR.

Copies of this patent may be obtained for five cents each, by addressing the "Commissioner of Patents, Washington, D. C."
